(57) **CLAIM**

The ornamental design for a window portion of a stampless envelope, as shown and described.

DESCRIPTION

The FIGURE is a front elevational view portion of a stampless envelope showing our new design, the remaining portions of the envelope including additional windows being shown for environmental purposes only and forming no part of the claimed design.

The broken lines defining the boundaries, and the FIM code within the claimed area in the FIGURE are shown for illustrative purposes only and form no part of the claimed design.
